UNITED STATES PATENT OFFICE.

WILLIAM O. DUNTLEY, OF CHICAGO, ILLINOIS, ASSIGNOR TO CHICAGO PNEUMATIC TOOL COMPANY, OF CHICAGO, ILLINOIS, A CORPORATION OF NEW JERSEY.

ENGINE.

No. 866,922.

Specification of Letters Patent.

Patented Sept. 24, 1907.

Application filed April 8, 1907. Serial No. 366,988.

To all whom it may concern:

Be it known that I, WILLIAM O. DUNTLEY, a citizen of the United States, residing at Chicago, Cook county, Illinois, have invented certain new and useful Improvements in Engines or Drills, of which the following is a specification.

My invention relates in general to a portable fluid pressure operated engine adapted more particularly as the engine or motor of rotary tools of various characters, such as drills and the like and my invention has for its object the production of a simple and efficient engine of this character of maximum power in proportion to its size and weight and embodying a novel and useful construction and arrangement of working parts all assembled and compactly combined and inclosed within a supporting casing.

The principal object of my invention is to provide a multiple cylinder fluid pressure operated engine or drill in which a single valve is arranged to control the admission and exhaust of motive fluid to and from all of the cylinders and in the reversible form of, engine or drill, to also serve as a reversing valve to control the direction of rotation of the drill shaft or spindle, thereby simplifying the valve mechanism, reducing the number of the parts and making the machine or engine more durable and effective.

In the preferred and herein illustrated embodiment of my invention, the engine or drill consists of a series or plurality of cylinders having pistons connected with a crank shaft which is common to all of them, to and from which cylinders the motive fluid is admitted and released by means of a single valve which, in such embodiment of my invention, is a rotatable valve actuated or rotated by the tool shaft or spindle. Moreover the arrangement is such that upon the longitudinal movement or adjustment of this single valve the direction of rotation of the engine may be reversed.

The different features of advantage and utility possessed by my engine or drill will be apparent from the description hereinafter given.

In the drawings Figure 1 is a vertical central section taken on line 1—1 of Fig. 2; Fig. 2 a transverse section on line 2—2 of Fig. 1; Fig. 3 a vertical section on line 3—3 of Fig. 2; Fig. 4 an enlarged view of the valve casting in vertical section and of the valve in elevation; Fig. 5 a view similar to Fig. 4 but in a plane at right angles thereto; Fig. 6 a section of the valve on line 6—6 of Fig. 4; Fig. 7 a section of the valve on line 7—7 of Fig. 4, and Fig. 8 a detailed view of the feed screw nut, etc. 50 The same reference characters are used to designate the same parts in the several figures of the drawings.

Referring to the illustrated embodiment of my invention, the drill or engine is provided with a casing A

which incloses and supports the plurality of cylinders, the pistons, the single valve, and of the crank shaft common to all of the pistons. The cylinders, in the present instance, are four in number marked A', A², A³, and A⁴ preferably cast integral with the casing and arranged in two sets lying in different and parallel planes, each set comprising two cylinders with their axes at right angles to each other and connected with the same crank of the crank shaft as hereinafter described. As shown, the cylinders A' and A² of one set are in the same horizontal plane while the cylinders A³ and A⁴ of the second set are in the same horizontal plane but below the plane of the cylinders A' and A². Each of the cylinders is provided with a removable cylinder head a by means of which access may be readily had to the interior of the cylinders, such head in the present instance screwing into the outer end of the cylinder.

The inner ends of the cylinders communicate with a crank shaft chamber formed in connection with the main casing A by means of a removable wall or curved plate A⁵ which is secured to the main casing in any suitable manner as by means of the lugs a⁶ fastened to such main casing. This curved plate is, in the present instance, provided with a screw threaded boss a⁷ to which a handle (not shown) for supporting the drill or engine may be readily secured. At a point opposite the handle connection of boss a⁷ the casing is provided with another boss a⁸ adapted to receive another handle which, in the present instance, is designed to be the live handle inasmuch as it is intended to be hollow to serve as a conduit for the motive fluid from the source of supply, through the boss a⁸ to the engine. Such handle arrangement being well known and forming no part of my present invention is not illustrated and need not be further described.

The lower end of the main casing is provided with a gear casing or cap C arranged to contain and inclose the gearing hereinafter described and the same is secured in suitable manner to the main casing as by means of a marginal flange and screws c. The opposite end of the main casing is closed by a top cap D which is secured to such casing in suitable manner as by means of the screws d.

The crank shaft K is located within the chamber formed by the wall or plate A⁵ as already described and the same is journaled in suitable bearings, the upper end thereof being journaled in the bearings d² supported in the top cap D and closed by the screw plug D², and the lower end thereof being journaled in similar bearings c² supported in the gear casing C and closed at the lower end by the screw plug C². The crank shaft is also journaled intermediate its length 105 in a bearing formed by a bushing c³ inserted within

the central flanged opening of plate C³ which is suitably secured to the lower end of the crank chamber, the same, in the present instance, being clamped in place by the same screws c which serve to secure the 5 gear casing to the main casing of the engine.

That portion of the crank shaft which is located within the crank shaft chamber proper is provided with two cranks K' and K² located 180° apart, one of the cranks coöperating with the pistons of one set of 10 cylinders and the other crank with the pistons of the other set of cylinders. As shown more particularly in Figs. 2 and 3 the crank K' is operatively connected with the ends of the piston rods g' and g² of the pistons G' and G² which are arranged to reciprocate in 15 the cylinders A' and A² respectively. In like manner the crank K² is operatively connected with piston rods g³ and g⁴ of the pistons G³ and G⁴ which are arranged to reciprocate within the cylinders A³ and A⁴ respectively, representing the set of cylinders in 20 the lower plane. The piston rods may be connected at their outer ends to their respective pistons in any suitable manner but in the present instance I have shown a ball and socket joint or connection comprising a ball g on the end of each piston rod seated in a 25 socket formed at its corresponding piston, a plug G, whose inner end forms a portion of the socket being screwed into the piston to retain the ball in place. Likewise any suitable connection may be employed between the piston rods and the cranks but according 30 to the preferred form as herein shown the piston rods g' and g² are provided with two-part collars or straps H' and H² which surround the cranks and are secured to the piston rods by internally screw threaded rings h which surround the screw threaded shanks H of 35 the two parts of the collar. The other piston rods g³ and g⁴ are, in similar manner, connected to the cranks by two-part collars or straps H³ and H⁴. These collars are also connected with the piston rods g² and g⁴ by means of internally screw threaded rings h which 40 surround the externally screw threaded shanks H of these collars.

As shown more particularly in Figs. 1 and 2 a feed screw N extends through an opening D' in the cap D, the same terminating in an enlarged and cylindrical 45 lower end, the remainder of the screw being externally screw threaded. The enlarged lower end of the feed screw passes through an opening or bearing A⁶ through which it is arranged to slide but prevented from rotation or axial movement by means of the key or feather a⁶. The feed screw is limited in its upward 50 movement by means of the marginal flange n' which bears against a shoulder formed in the bearing A⁶.

The tool spindle or shaft L whose lower end projects through the bottom of the gear casing and is screw 55 threaded thereto to receive the tool chuck or other means for holding the working tool, is provided intermediate its length with a driving gear l arranged within the gear casing. The upper end of the tool spindle or shaft is reduced in diameter so as to project upwardly 60 and be received within the lower end of the hollow feed screw, a bushing n' being interposed between such tool spindle and the body of the feed screw. By preference ball bearings are interposed between the lower end of the feed screw and a shoulder or collar l² formed on the 65 tool spindle and in the present instance such bearings

comprise the two disks or rings n³ and l³ bearing respectively against the feed screw N and the collar or shoulder l² and providing between them a race-way for the balls. At a point within the gear casing the tool spindle has secured to it a gear L⁵ which is arranged to 70 mesh with the pinion E⁵ which in the present instance is formed upon the lower end of the rotatable valve hereinafter described. The motion of the crank shaft is transmitted to the tool spindle through the pinion k formed upon the crank shaft itself, as seen in Fig. 1 75 and meshing with the gear l which is secured to the tool spindle, as already described. The tool spindle has its bearings at its upper end within the hollow feed screw as already stated while the lower end has its bearings in the lower wall or bottom of the gear casing, such 80 latter bearing being composed of a bushing c' passing through the opening in the gear casing provided with the flange C' on which also screws the usual ring c'. It will be understood that while in the present instance the pinion k is formed as a part of the crank shaft by 85 simply cutting grooves therein as shown in Figs. 1 and 3, such particular construction, while desirable, is not essential to the successful operation of my engine or drill.

For the purpose of operating the feed screw and at 90 the same time providing a grasping handle which is useful in connection with the handles in some kinds of work such as reaming, I provide the handle M which has an internally screw threaded extension or socket m arranged to engage the externally screw threaded feed 95 screw, N. This handle extension is provided, in the present instance, with a collar m' which is adapted to bear against the upper edge of the flange surrounding the opening D' in the top cap D into which the lower end of the handle extension enters. 100

As hereinbefore stated the motive fluid to and from the plurality of cylinders is controlled by a single valve whereby such motive fluid is admitted to and released from the various cylinders in sequence for the rotation of the crank shaft and consequent rotation of the tool 105 spindle and such valve is likewise so constructed and arranged that by manual adjustment thereof the same may be constructed to so control the motive fluid as to reverse the direction of rotation of such crank shaft and tool spindle, such valve being preferably held in one 110 position or the other with a yielding pressure.

As herein shown, the valve E is substantially cylindrical in general form and is located within the cylindrical casing B arranged within the main casing within the trough formed by the two sets of cylinders and towards the upper end of such trough. By preference this casing B is formed integral with the main casing and is provided with a valve case or bushing b' within which the valve B is adapted to operate. 115

From the valve case extend two sets of main passages, 120 the first set B' and B² leading to the ends of the cylinders A' and A² whereby the motive fluid is alternately admitted thereto and exhausted therefrom and the second set of similar passages B³ and B⁴ leading to the ends of the cylinders A³ and A⁴, likewise for the alternate admission of motive fluid thereto and its exhaust therefrom. The main air inlet formed in the boss a' communicates directly with the longitudinal passage a² extending along the side of the valve case and the same communicates with the interior of each valve 125 130

case through the central port b^2 and the two end ports b' and b^3 , such three ports constituting inlets for the motive fluid into the valve case.

As shown more clearly in Figs. 4 and 5 the valve E is provided with three reduced portions forming the three annular grooves e' , e^2 and e^3 which register respectively with the ports b' , b^2 and b^3 . In the two heads formed on either side of the middle groove e^2 are formed a series of inlet channels and also a series of exhaust ports for properly controlling the admission and exhaust of the motive fluid in operating the engine in either direction. Referring first to the ports and inlet channels formed in the head or portion of the valve above the annular groove e^2 , two series of three ports each are provided, the same leading inwardly and communicating with the longitudinal exhaust passage e which extends downwardly and exhausts into the gear case from which the exhaust escapes through the openings C^4 in the sides of such casing. The two series of exhaust ports are arranged in two sets lying in different planes the upper set F^3 being effective and active when the engine is working in one direction and the other set F^4 being at this time inactive but arranged to become active when the valve is adjusted or longitudinally moved for the purpose of operating the engine in the reverse direction, in the manner hereinafter explained. The channels E^3 communicate at all times with the annular groove e^2 for the purpose of conducting the motive fluid from such groove alternately to the passages B' and B^2 leading to their respective set of cylinders. The other set of channels E^4 communicate with the annular groove e^2 for the purpose of conducting the motive fluid therefrom alternately to said passages B' and B^2 when the valve is adjusted or moved upwardly from the position indicated in the drawings. In similar manner the head or portion of the valve between the annular grooves e' and e^2 is provided with separate sets of exhaust ports for the exhaust of the motive fluid and separate sets of channels for the inlet of the motive fluid. As shown, the valve is thereat provided with the series of three channels E^2 corresponding to the channel E^3 and arranged to conduct the motive fluid from the groove e^2 to the passages B^3 and B^4 leading to the lower set of cylinders A^3 and A^4 according to the illustrated position of the valve and when, in the rotation of the valve, such channels are presented or brought into register with said passages B^3 and B^4 . The series of exhaust ports and passages which correspond with the channels e^2 are marked F^2 and the same communicate with the longitudinal air passage e in the valve and are arranged to exhaust the cylinders A^3 and A^4 through said passages B^3 and B^4 when such exhaust ports are presented to said last named passages. This particular portion or head of the valve is provided with another set of channels E' corresponding with the channels E^2 and arranged to conduct the motive fluid from the groove e' to said passages B^3 and B^4 but inactive or ineffective whenever the corresponding grooves E^4 are inactive, that is when the valve is in the position illustrated in the drawing. Corresponding with these channels E' is a series of exhaust ports F' communicating with the longitudinal exhaust passage e in the valve and adapted to exhaust the motive fluid from the passages B^3 and B^4 when the valve is adjusted from the position indicated in the drawings and when such

ports are brought into register with said passages B^3 and B^4 in the rotations of the valve.

It will be observed that the series of channels and exhaust ports are arranged in staggered relation as clearly indicated in Figs. 4 and 5 where it is seen, for instance, that the exhaust ports have their corresponding channels alternate and also that the channels of one set or series are not in alignment with the channels of the set or series in the same valve head or portion but are staggered with relation thereto. Thus the channels E^3 are located immediately above the exhaust ports F^4 while the exhaust ports F^3 are located immediately above or in alignment with the channels E^4 . So also in the other valve head the exhaust ports F^2 are located above or in alignment with the channels E' while the channels E^2 are located above or in alignment with the exhaust ports F' . The result of this alignment of ports and passages is such as to cause a reversal of the direction of rotation of the engine or drill whenever the valve is adjusted or moved upwardly from the position indicated in the drawings so as to render active the series of channels E' and E^4 and likewise the series of exhaust ports F' and F^4 , which, in the illustrated position, are inactive and ineffective. The upper or closed end of the valve is provided with a rod or stem F which, while held against rotation, is arranged to engage the valve so that the latter may be moved longitudinally by means of such rod or stem but without interfering with the free rotation of such valve. In the present instance I accomplish this result by providing a ball and socket connection between the valve and lower end of the rod, which latter is provided with the ball f fitted within a socket formed in the upper end of the valve body and held in place by the retaining disk or plate f' which is secured to the valve body in any suitable manner. The rod or valve stem has its bearings in the boss D^3 extending upwardly from the top cap D and the same terminates in a hand piece or wheel f^2 for manual operation. For the purpose of holding or maintaining the valve in one or the other positions to which it is adjustable, I provide suitable means arranged to coöperate with the valve stem with a yielding pressure. As shown in Fig. 1, one side of the valve stem is provided with two recesses f^3 adapted to be engaged by the spring pressed pin 110 d^3 and located at such points along the length of the valve stem that when the pin engages the upper recess the valve is in proper position for controlling the motive fluid in one direction or rotation of the engine and that when the pin d^3 is in engagement with the lower recess the valve is in proper adjusted position for controlling the motive fluid when the engine is running in the opposite direction. Describing a cycle of operation of the engine and starting with the parts in their relative positions as herein illustrated, the motive fluid passes from the supply conduit such as the live handle (not shown) through the boss a' to the longitudinal passage a^2 from whence it is distributed through the always open ports b' , b^2 and b^3 to the annular grooves e' , e^2 and e^3 respectively. In this particular adjustment of the valve the motive fluid supplied to the two upper annular grooves e^2 and e^3 is admitted, at the proper time, to the different cylinders by means of the series of channels E^2 and E^3 but, as is evident, the motive fluid 130

which enters the lower annular groove e' is not admitted anywhere in this adjustment of the valve inasmuch as its admission channels E' are at this time inactive. The admission of the motive fluid to the 5 cylinders in succession causes a rotation of the crank shaft which is common to all of the pistons of these cylinders and the rotation of such crank shaft is communicated through the pinion k to the gear l whereby the tool shaft or spindle is rotated. The rotation of the 10 tool shaft causes a rotation of the valve E through the gear L' secured to the tool spindle and the pinion E' formed at the lower end of the valve, which pinion is always in engagement with its gear L' to whatever position the valve may be adjusted, the pinion being 15 elongated for this purpose. In this manner the valve E is rotated so as to alternately present its active inlet channels and active exhaust ports alternately to the passages leading to the plurality of cylinders.

When the valve is in the position shown in Fig. 2 20 the motive fluid passes to the cylinder A' from the groove e^3 and through one of the channels E^3 , and thence through the passage B' to said cylinder A' . The valve E moving in a clockwise direction (Fig. 2) the motive fluid is supplied to the cylinder A^2 by a 25 further rotation of the valve through another one of the inlet channels E^3 , it being understood that one of the exhaust ports F^3 has just been rotated out of register with the passage B^2 , with which one of the inlet channels E^3 is now brought into register. At or about this 30 time the admission of motive fluid through the passage B' is cut off and one of the exhaust ports F^3 is brought into register with said passage B' and the cylinder A' thereby exhausted, such operations following each other successively in the rotations of the engine. In 35 like manner the motive fluid is supplied to the cylinders A^3 and A^4 from the annular groove e^2 by means of the inlet channels E^2 and the passages B^3 and B^4 , the relative arrangement of the inlet channels and exhaust ports of the lower set of cylinders being staggered 40 or out of alignment with the correspondingly active channels E^3 and exhaust ports F^3 with the result that the motive fluid is admitted through the passages B' and B^4 at or about the same time and exhausted through the other two passages B^2 and B^3 , and vice 45 versa, alternately in the rotations of the valve.

According to the particular construction illustrated in the drawings, wherein each set of inlet and exhaust passages comprises three passages spaced around the circumference of the valve, (for instance the set of inlet passages E^3 illustrated in Fig. 6 are three in number and the same is true of the set of exhaust ports F^3 equidistantly spaced on the circumference of the valve) it is evident that each piston makes three complete strokes or cycles and consequently the crank 55 shaft makes three complete rotations for every rotation of the valve. The proper movement or timing of the valve is obtained by the proper relative sizes of the gearing which drives such valves, it being understood that the valve is driven or rotated through the medium 60 of the pinion E^5 secured to or formed at its lower end and the gear L' which meshes therewith and which is mounted or secured upon the tool spindle L . As hereinbefore stated, the tool spindle is itself driven or rotated through the medium of its gear l and the pinion 65 k secured to or formed as a part of the crank shaft of

the engine. The proper governing of the different cylinders by means of the valve is thus obtained without any excessive speed of rotation of the valve which has a speed of only 1 to 3 as compared with the speed of rotation of the crank shaft of the machine. 70

When it is desired to reverse the direction of rotation, the valve is moved or adjusted upwardly longitudinally by an upward pull of the valve rod or stem F , at which time the spring pressed pin will engage the lower recess f^3 and thereby hold the valve in such adjusted position. This adjustment of the valve brings the inlet channels and exhaust ports, heretofore inactive, to an active position and at the same time renders active such heretofore inactive channels and exhaust ports. In other words the inlet channels E^4 and the exhaust ports F^4 are brought into position so as to coöperate with the passages B^3 and B^2 of the upper set of cylinders and to control the motive fluid thereto and therefrom, and in like manner the inlet channels E' and the exhaust ports F' are brought into 80 coöperative relationship with the passages B^3 and B^1 of the lower set of cylinders and the same are thereby enabled to control the motive fluid to and from such cylinders. In this position of the valve the live motive fluid which enters the annular groove e^2 is admitted to the upper 90 set of cylinders through the passages B' and B^2 through the channels E^4 and exhausted therefrom by the exhaust ports F^4 , while the motive fluid to the lower set of cylinders is admitted from the annular groove e' and channels E' to the passages B^3 and B^4 and exhausted 95 therefrom through the exhaust ports F' . It is understood that owing to the staggered relationship of the inlet channels to the exhaust ports in the two upper series and the corresponding staggered relationship of the channels and exhaust ports in the lower series, the 100 described adjustment of the valve causes a reversal of the successive admission and exhaust of motive fluid to and from the cylinders so that the direction of rotation of the crank shaft is reversed.

From the foregoing description it will be observed 105 that my fluid pressure operated engine or drill is simple in construction and operation and is most compact considering the power or energy developed. Moreover the motive fluid to and from the plurality of cylinders is entirely under the control of a single valve which, 110 by a simple adjustment in position thereof, is enabled to cause a reversal of the direction of rotation of the engine or drill. The single valve is therefore both a controlling valve and a reversing valve.

The handle M hereinbefore referred to is simply a 115 grasping handle and does not coöperate with or actuate the force feed mechanism other than to simply screw upon the feed screw N , whereby the grasping handle is conveniently held, in a removable manner, to the engine or drill. When the engine or drill is employed 120 with a force feed device, the handle M is removed and the feed screw N is provided with a cylindrical feed screw sleeve or nut O which is internally screw threaded so as to engage the external screw threads of the feed screw. This nut is provided with the usual centering point O at its upper end and also with the hand wheel or pilot O' which is common in force feed devices of this general character. This construction and arrangement is illustrated by Fig. 8 which shows the parts on a somewhat reduced scale as compared with 130

the other figures. This form of force feed being well-known it is sufficient to say that upon rotation of the pilot in the proper direction while the centering point is bearing against a fixed abutment, the drill is properly fed to and through the work as required in the drilling operation.

I claim:

1. In a fluid pressure operated drill, the combination of a plurality of cylinders arranged in two sets lying in parallel planes each set comprising two cylinders with axes at right angles, pistons in the cylinders connected with a common crank shaft, and a single rotatable valve controlling the admission and exhaust of the motive fluid to and from all of the cylinders, said valve having two sets or series of ports and passages for such admission and exhaust, one set being effective when the valve is in one position to cause rotation of the drill in one direction and the other set being at such time ineffective but arranged to admit and exhaust motive fluid to and from the cylinder when the valve is adjusted to another position to cause rotation of the drill in the reverse direction. 10

2. In a fluid pressure operated drill, the combination of a plurality of cylinders arranged in two sets lying in parallel planes, each set comprising two cylinders with axes at right angles, pistons in the cylinders connected with a common crank shaft, a single rotatable valve for controlling the admission and exhaust of motive fluid to and from all the cylinders, and means for shifting the valve longitudinally for reversing the drill and holding the same 15 in adjusted position with a yielding pressure.

3. In a fluid pressure operated drill, the combination of a plurality of cylinders arranged in two sets lying in parallel planes, each set comprising two cylinders with axes at right angles, pistons in the cylinders connected with a common crank shaft, a single rotatable valve for controlling the admission and exhaust of motive fluid to and from all the cylinders, a rod or stem connected with the valve whereby the latter may be shifted longitudinally for reversing the drill, and means for holding said rod or stem 20 in one position or the other with a yielding pressure.

4. In a fluid pressure operated drill, the combination of a plurality of cylinders arranged in two sets lying in parallel planes, each set comprising two cylinders with axes at right angles, pistons in the cylinders connected with a common crank shaft, a single rotatable valve for controlling the admission and exhaust of motive fluid to and from all the cylinders, a rod or stem connected with the valve whereby the latter may be shifted longitudinally for reversing the drill, and means for holding said rod or stem 25 in one position or the other with a yielding pressure, comprising a spring pressed pin engaging said valve stem.

5. In a fluid pressure operated drill, the combination of a plurality of cylinders arranged in two sets lying in parallel planes, each set comprising two cylinders with axes at right angles, pistons in the cylinders connected with a common crank shaft, a single rotatable valve for controlling the admission and exhaust of motive fluid to and from all the cylinders, a rod or stem having a ball and socket connection with the valve whereby the latter may 30 be shifted for reversing the drill, and means for maintaining the valve stem and valve in one position or the other according to the desired direction of rotation of the drill.

6. In a fluid pressure operated drill, the combination with a plurality of cylinders having motive fluid passages communicating therewith, pistons in said cylinders, a driven element to which said pistons are operatively connected, a valve casing with which said passages communicate, a single valve within said casing having one series of ports for controlling the supply and exhaust of motive fluid to and from a plurality of the cylinders to rotate the driven element in one direction, and a second series of ports for controlling the supply and exhaust of motive fluid to and from said plurality of cylinders to rotate the driven element in a reverse direction, means for actuating said valve to control the supply and exhaust of motive fluid, and means for adjusting the position of the ports thereof with respect to said passages to determine the direction of rotation of said element. 35

7. In a fluid pressure operated drill, the combination with a plurality of cylinders having motive fluid passages communicating therewith, pistons in said cylinders, a driven element to which said pistons are operatively connected, a valve casing with which said passages communicate, a single valve within said casing having one series of ports for controlling the supply and exhaust of motive fluid to and from all of the cylinders, said valve having two sets or series of ports and passages for such admission and exhaust, one set being effective when the valve is in one position to cause rotation of the drill in one direction and the other set being at such time ineffective but arranged to admit and exhaust motive fluid to and from the cylinder when the valve is adjusted to another position to cause rotation of the drill in the reverse direction. 40

8. In a fluid pressure operated drill, the combination with a pair of cylinders having motive fluid passages communicating therewith, of pistons in said cylinders, a driven element to which said pistons are operatively connected, a valve casing with which said passages communicate, a single valve within said casing having one series of ports for controlling the supply and exhaust of motive fluid to and from the pair of cylinders to rotate the driven element in one direction and a second series of ports for controlling the supply and exhaust of motive fluid to and from said pair of cylinders to rotate the driven element in a reverse direction, means for adjusting the position of the valve to bring either series of ports into alignment with said passages, and means for actuating said valve to control the supply and exhaust of motive fluid. 45

9. In a fluid pressure operated drill, the combination with two pairs of cylinders having motive fluid supply and exhaust passages leading thereto, of pistons in said cylinders, a driven element to which said pistons are operatively connected, a valve casing with which said passages communicate, a single valve located within said casing and having one series of ports for controlling the supply and exhaust of motive fluid to and from one pair of cylinders and a second series of ports for controlling the supply and exhaust of motive fluid to the other pair of cylinders to rotate the driven element in one direction, a third series of ports for controlling the supply and exhaust of motive fluid to the first pair of cylinders to rotate the driven element in a reverse direction, and a fourth series of ports to control the supply and exhaust of motive fluid to the second pair of cylinders to rotate the driven element in said reverse direction, means for actuating said valve to control the supply and exhaust of motive fluid, and means for adjusting the position of the valve to bring either said first and second series of ports or said third and fourth series of ports into alignment with said passages according to the direction in which the element is to be rotated. 50

10. In a fluid pressure operated drill, the combination with a pair of cylinders having motive fluid passages communicating therewith, of pistons in said cylinders, a driven element to which said pistons are operatively connected, a valve casing with which said passages communicate, a cylindrical valve located within said casing having a central exhaust passage and two parallel series of radial exhaust ports leading thereto, said valve having inlet channels intermediate of the exhaust ports in each series, means for rotating said valve to control the supply and exhaust of motive fluid to and from said passages, and means for moving said valve axially to bring either series of ports and channels into alignment with said passages. 55

11. In a fluid pressure operated drill, the combination with a pair of cylinders having motive fluid passages communicating therewith, of pistons in said cylinders, a driven element to which said pistons are operatively connected, a valve casing with which said passages communicate, a cylindrical valve located within said casing having a central exhaust passage and two parallel series of radial exhaust ports leading thereto, said valve having inlet channels intermediate of the exhaust ports in each series, means for rotating said valve to control the supply and exhaust of motive fluid to and from said passages, 60

- a rod connected to one end of said valve for moving the same axially, and means engaging said rod to lock the same in position to locate either of said series of ports and channels in alignment with said passages.
- 5 12. In a fluid pressure operated drill, the combination with a pair of cylinders having motive fluid passages communicating therewith, of pistons in said cylinders, a driven element to which said pistons are operatively connected, a valve casing with which said passages communicate, a hollow cylindrical valve having two circular grooves in its surface and two series of channels between said grooves each series comprising surface channels leading from the adjacent grooves and exhaust ports communicating with the hollow center of the valve intermediate of the supply ports, the supply and exhaust ports in the two series being staggered, means for axially adjusting said valve to bring either series of ports and channels in alignment with said passages, and means for actuating said valve to control the supply and exhaust 20 of motive fluid.
13. In a fluid pressure operated drill, the combination with two pairs of cylinders having motive fluid supply and exhaust passages leading thereto, of pistons in said cylinders, a driven element to which said pistons are operatively connected, a valve casing with which said passages communicate, a hollow cylindrical valve having three circular grooves in its surface and two series of ports and passages between the intermediate and each end 25 channel, each series of ports and passages comprising surface supply channels leading from the adjacent grooves and exhaust ports communicating with the interior of the hollow valve and intermediate to the supply channels, the supply channels and exhaust ports in adjacent series being staggered, means for axially ad-
- justing said valve to vary the positions of the series of 35 ports with respect to said passages to determine the direction of rotation of the driven element, and means for rotating said valve to control the supply and exhaust of motive fluid.
14. In a fluid pressure operated drill, the combination 40 of a plurality of cylinders, pistons therein, a crank shaft common to said pistons, a valve for controlling the admission and exhaust of the motive fluid to and from the cylinders, said valve being adjustable to reverse the direction of rotation of the crank shaft, and means for holding the valve in its adjusted position comprising a rod or stem connected with the valve and having two recesses at different positions along its length, and a spring pressed pin arranged to engage one or the other of said recesses to hold the valve in one or the other of its adjusted 45 positions.
15. In a fluid pressure operated drill, the combination 50 of a plurality of cylinders, pistons therein, a crank shaft common to said pistons, a valve for controlling the admission and exhaust of the motive fluid to and from the cylinders, said valve being adjustable to reverse the direction of rotation of the crank shaft, and means for holding the valve in its adjusted position comprising a rod or stem having a ball and socket connection with the valve and provided along its length with two recesses at 55 different positions, and a spring pressed pin arranged to engage one or the other of said recesses to hold the valve in one or the other of its adjusted 60 positions.

WILLIAM O. DUNTLEY.
